UNITED STATES PATENT OFFICE.

ALBERT J. HORTON, OF WHITE PLAINS, NEW YORK, ASSIGNEE TO THE CUTLER-HAMMER MFG. CO., OF MILWAUKEE, WISCONSIN, A CORPORATION OF WISCONSIN.

CIRCUIT-CONTROLLER.

1,199,985.

Specification of Letters Patent.

Patented Oct. 3, 1916.

Application filed October 18, 1911. Serial No. 654,878.

To all whom it may concern:

Be it known that I, ALBERT J. HORTON, a citizen of the United States, residing at White Plains, in the county of Westchester 5 and State of New York, have invented new and useful Improvements in Circuit-Controllers, of which the following is a full, clear, concise, and exact description, reference being had to the accompanying drawing, forming a part of this specification.

My invention relates to improvements in circuit controllers.

It has among its objects to provide a circuit controller comprising a plurality of 15 switches interlocked in such a manner that one or the other of the switches is always locked in a predetermined position and is only movable from such position when the other switch is moved to a predetermined 20 position.

A further object is to provide a circuit controller whereby two or more batteries may each be connected to a common charge or discharge circuit or either may be entirely disconnected from circuit but which 25 will insure the connection of at least one battery to the discharge circuit at all times.

Other objects and advantages will be hereinafter set forth.

For the purpose of clearly and fully setting forth the nature and characteristic features of my invention, I shall describe the circuit controller shown in the accompanying drawing which embodies my invention 35 in one form.

In the accompanying drawings: Figure 1 is a plan view of the circuit controlling device, Fig. 2 is an end view of Fig. 1 and Fig. 3 is a diagrammatic view of a controlling system employing the controller shown in Figs. 1 and 2.

The device selected for the purpose of illustration comprises two double pole knife switches 1 and 2 mounted upon a suitable 45 insulating supporting panel 3. Both switches are of the same construction and of a conventional type. Description of one switch will accordingly suffice for both.

The switch 1 comprises blades a' and b' pivoted to contacts c' and d' respectively and connected at their opposite ends by an insulating cross bar e' having a suitable handle f' . As is customary the cross bar e' extends beyond the switch blades. The

switch blades have two operative positions, 55 one in which they engage contacts g' and h' as shown in full lines, and the other in which they engage contacts j' and k' as shown in dotted lines. For the convenience of distinguishing between the various parts 60 of the two switches in later describing the circuit connections controlled thereby, I have designated like parts of the switch 2 by the same reference letters, but with the exponent 2 instead of the exponent 1.

The switches 1 and 2 are provided with an interlock necessitating placing both switches in the positions illustrated before either switch can be moved from such position. In other words, the interlock is such 70 that should the switch 2 for example, be in the dotted line position, the switch 1 could not be moved from the full line position until the switch 2 had first been moved to the full line position.

The interlocking means shown is very simple and is as follows:—The insulating cross bars e' and e^2 are provided at adjacent ends with oppositely projecting pins z' and z^2 . These pins are adapted to be engaged to lock the switches in the full line positions by hooks or latches m' and m^2 respectively. Each of these hooks as is best illustrated in Fig. 2 is fulcrumed upon a spindle, each spindle being supported in 85 the upturned ends α of a plate p suitably secured to the insulating base 3. An ordinary screw or bolt may be employed for the spindle. Surrounding the spindle is a coil 90 spring q having one end secured to the hook or latch member and its opposite end secured to the supporting plate p . This spring holds the latch against longitudinal movement on its spindle and also biases the latch in a direction to engage the pin 95 on its corresponding switch. Each of the latches is provided with a tail piece r and the insulating cross members e' and e^2 of the switches have fixed thereto on opposite sides of contiguous ends downwardly projecting lugs s and s' adapted to engage the tail pieces of the latches m' and m^2 respectively. These lugs may be of any preferred character and either formed integrally with the insulating members of the switches or attached thereto in any preferred manner.

By means of these lugs whenever either switch is thrown to the full line position it

will engage and rock the latch of the other switch to release the same and permit it to be moved to the dotted line position. When both switches are in the full line positions each will release the other so that either one may be operated. However, as soon as one switch is moved away from the full line position it disengages the latch of the other switch which under the influence of the spring engages the pin of the latter switch locking said latter switch against operation.

I am of course aware that the same interlock might be obtained by various other means and that the same interlock might be accomplished for various other than the knife type of switches. Devices embodying such an interlock as that described have a wide range of application, being adapted for use in various different relations and for various different purposes.

The device chosen for the purpose of illustration is particularly adapted for use in a charging and discharging system such as is used in connection with electrically controlled clocks. For the purpose of illustration I have accordingly shown the device used in such a relation in Fig. 3. In this figure I have shown the switches 1 and 2 as controlling the charging and discharging circuits of storage batteries B' and B^2 . These batteries are adapted to discharge through a circuit 4-5 and to be charged from a circuit 6-7 through a suitable charging rheostat 9. In the charging circuit is also included a protective device 10 comprising an arm carrying a bridging contact 11. This arm is held in operative position by a latch 12, which latch is adapted to be tripped to release the arm 10 by a magnet 13. This magnet is adapted to be connected across the charging circuit by movement of either switch 1 or switch 2 to its dotted line position, this being accomplished through auxiliary contacts 14 and 15 arranged to be engaged by adjacent blades of the switches 1 and 2 respectively. In such a system as that shown it is always essential to have at least one battery connected to the discharge circuit at all times. The device shown in Fig. 1 positively insures this result.

I shall now describe the operation and functions of the circuit controller illustrated, at the same time specifically setting forth the circuit connections therefor. Assuming both switches to be in full line positions both batteries will be connected to the discharge circuit. The battery B' will discharge from its positive side by conductor 16 to blade b' of switch 1 to contact k' by conductors 17 and 18 to discharge line 5. The return circuit will be from discharge line 4 by conductor 19 to contact g' of switch 1 by conductor 20 to the negative terminal

of the battery B' . The terminals of battery B^2 are directly connected to the blades of switch 2. The contacts g^2 and h^2 are cross connected to the contacts h' and g' of switch 1 respectively, and accordingly the battery B^2 will also be connected to the discharging circuit. Assuming now that the switch 1 be opened, the battery B^2 alone will be connected to the discharge circuit. Battery B' will be entirely cut out. Battery B' may at this time be charged by throwing the switch 1 to the dotted line position. This will complete a circuit from charging line 7, by conductors 21 and 22 to contact k' of switch 1, blade b' , conductor 16 through the battery B' from plus to minus by conductor 20 to blade a' , contact F' by conductor 22, protective device 10, through the rheostat 9 to charging line 6. Also a branch circuit will be established from blade b' of switch 1 by contact 14, conductors 23 and 24

through the resistance 25, magnet 13, conductor 26, arm 10 and through the charging rheostat, thereby connecting the magnet 13 across the charging line to limit the potential impressed upon the storage battery. If now it is desired to charge the battery B^2 which requires throwing the switch 2 to the dotted line position, it is imperative by virtue of the interlock between the switches to first move the switch 1 to its full line position. When this has been done the switch 2 may be opened which results in immediately locking the switch 1 in full line position, connecting the battery B' to the discharge circuit 4-5. This as is obvious, insures one battery being connected to the discharge circuit at all times. If the switch 2 be left in open position, the battery B^2 will be entirely disconnected from circuit. If the switch 2 be moved to dotted line position, it will connect the battery B^2 to the charging circuit. Since the contacts j^2 and h^2 of switch 2 are cross connected to contacts k' and j' of switch 1 respectively, it is obvious that movement of the switch 2 to engage contacts j^2 and h^2 will connect the storage battery to the charging circuit. Thus it is entirely unnecessary to trace the circuit.

What I claim as new and desire to secure by Letters Patent is as follows:—

1. In a circuit controller, in combination, two pivoted and separately operable switches and interlocking means controlled by said switches to positively lock one or the other of the same in all but a certain relation thereof whereby to insure reestablishment of such relation for release of the locked switch.

2. In a circuit controller, the combination with two pivoted and separately operable double-throw switches and an interlock between said switches acting to always lock one or the other of said switches in a selected extreme position thereby necessitating re-

turn of the free switch to its selected extreme position prior to release of the locked switch.

3. In a circuit controller, in combination, two separately operable switches and a latch for each of said switches governed by the other of said switches to always insure predetermined positioning of at least one of said switches.
4. In a circuit controller, in combination, two separately operable switches and a piv-

oted latch for each of said switches biased to locking position and subject to tripping by the other of said switches but only in the lockable position of the latter.

15

In witness whereof, I have hereunto subscribed my name in the presence of two witnesses.

ALBERT J. HORTON.
